GOVERNOR RESETTING DEVICE

Alan G. Day, West Hartford, Conn., assignor to
 United Aircraft Corporation, East Hartford,
 Conn., a corporation of Delaware

Application August 31, 1940, Serial No. 355,058

6 Claims. (Cl. 264—3)

This invention relates to improvements in speed responsive governors and has particular reference to an improved governor having manually operable means for changing the speed setting thereof.

An object of the invention resides in the provision in a speed responsive governor of the character indicated of means for automatically returning the governor to a predetermined speed setting in the event of failure of the manually controllable speed setting means.

Other objects and advantages will be more particularly pointed out hereinafter or will become apparent as the description proceeds.

In the accompanying drawing, in which like reference numerals are used to designate similar parts throughout, there is illustrated a suitable mechanical embodiment for the purpose of disclosing the invention. The drawing, however, is for the purpose of illustration only and is not to be taken as limiting or restricting the scope of the invention since it will be apparent to those skilled in the art that various changes in the illustrated embodiment may be resorted to without in any way exceeding the scope of the invention.

In the drawing, the single figure is a vertical sectional view through a governor showing an automatic resetting device, constructed according to the invention, applied thereto.

Referring to the drawing in detail, the numeral 10 generally indicates a governor pad which may be mounted upon an engine or other suitable support and provided with fluid passages in a manner well known to the art. This pad may include a governor actuated valve comprising the slidably plunger 12 and the rotatable drive shaft 14 which shaft may be driven from the engine through a suitable driving connection 16. At its end opposite the connection 16 the shaft projects into a governor housing 18 and carries a rotatable platform 20 upon which are mounted a plurality of governor flyballs, as indicated at 22 and 24. If desired, the platform 20 may also carry a rotatable cup 26 surrounding the flyballs to avoid damping of the rotational movements of the flyballs by any fluid such as lubricating oil, which might be contained in the housing. The plunger 12 also extends within the governor housing and is provided at its upper end with a thrust bearing 28 against which the bell crank arms of the flyballs 22 react to move the plunger relative to the sleeve 14 as the flyballs move in and out under the centrifugal forces incident to speed variations of the governor drive. The force exerted by the

5 flyballs 22 and 24 tending to lift the plunger 12 is resisted by a speeder spring 30 the lower end of which bears on an abutment 32 mounted on the upper end of the plunger 12 and the upper end of which bears against an adjustable abutment 34 mounted in a cylindrical extension 36 of the governor cap 37 secured in operative position on the top of the housing 18.

The abutment 34 may conveniently comprise 10 a cup shaped member 38 having a split externally threaded skirt portion received in an internally threaded sleeve member 40 reciprocable in the cylindrical extension 36 and a locking plug 42 for locking the members 38 and 40 together in adjusted position. The sleeve member 40 is provided along one side thereof with rack teeth 44 which mesh with the teeth of a pinion 46 rotatably mounted in the cap 37 on a shaft 50 one end of which projects outside of the cap to a connection with a pulley 52 manually rotatable by 15 suitable means including the cable 54. When the gear 46 is rotated by the pulley 52 and cable 54 the sleeve 40 will be moved up or down in the cylindrical extension 36 moving the abutment 34 to change the loading on the speeder spring 30 thereby changing the speed setting of the governor in a manner wellknown to the art. The manual adjusting means may be locked in operative position by suitable means as exemplified by 20 the lever 56 attached to the pulley 58, the lever carried detent 60 and the relatively fixed serrated quadrant 62.

With this arrangement, it is apparent that in 25 the event of failure of any essential part of the manual adjusting apparatus or the locking means therefor the load on the governor speeder spring 30 would be immediately relieved and a minimum speed setting of the governor would be established. If the governor were used, for example, to 30 control a controllable-pitch propeller this would mean that the propeller would go to a high pitch setting and a material part of its propulsive efficiency would be lost and it would be impossible to operate the propeller driving engine at a speed sufficient to obtain an engine power in the upper portion of the range of the power output capacity of the engine. In order to avoid such a contingency, the present improved governor is provided with an extension 64 beyond the cylindrical extension 36 receiving the sleeve 40 and separated from this cylindrical extension by an inwardly offset shoulder 66, and a compression spring 68 disposed within the additional extension 64 and bearing at its upper end against the closed end 40 of this extension and at its lower end against 50

the top of the movable abutment 34. The spring 68 exerts a force sufficient to load the spring 30 an amount sufficient to provide an intermediate governor speed setting such as would maintain a reasonable degree of efficiency of a power plant controlled by the governor. As long as the manual control and locking means therefor is fully operative the governor setting is completely under manual control and the spring 68 does not materially affect the positioning of the abutment 34 although, by balancing the force exerted on the abutment by the spring 30, it does relieve to a limited extent the force necessary to rotate the pulley 52. Its main function, however, is to provide an automatic resetting of the governor to a predetermined speed setting in the event control of the governor by the manual speed setting apparatus is lost.

While a suitable mechanical arrangement for disclosing the invention has been hereinabove described and illustrated in the accompanying drawing, it is to be understood that the invention is not limited to the particular arrangement so illustrated and described, but that such changes in the size, shape and arrangement of the various parts may be resorted to as come within the scope of the subjoined claims.

Having now described the invention so that others skilled in the art may clearly understand the same, what it is desired to secure by Letters Patent is as follows:

1. In a speed governor having a speeder spring and manually operable mechanism for changing the loading on said speeder spring, resilient means, exerting an increasing force on a portion of said manually operable mechanism as said mechanism is moved to decrease the loading on said speeder spring and exerting a decreasing force on said portion as said mechanism is moved to increase the loading on said speeder spring, for restoring the loading on said spring to a predetermined intermediate amount upon failure of other portions of said manually operable means.

2. In a speed governor having a speeder spring, a movable abutment for one end of said speeder

spring, and manually operable means for changing the loading on said speeder spring by moving said abutment, a second spring for exerting a force on said abutment equal and opposite to

5 the force exerted by said speeder spring and arranged to exert an increased force when the abutment is moved to decrease the force of said speeder spring and vice versa so that upon failure of said manually operable means said abutment 10 will be moved to a predetermined position and said speeder spring loading will revert to a predetermined value.

3. In a speed governor having a speeder spring, a movable abutment for said speeder spring, and 15 manually operable means for moving said abutment, a spring bearing upon the opposite side of said abutment from said speeder spring exerting a force on said abutment opposite to the force exerted thereon by said speeder spring.

20 4. In a speed governor having a speeder spring, a movable abutment for said speeder spring, a cylinder for said abutment, and manually operable means for moving said abutment, an extension on the end of said cylinder opposite said speeder spring, and a compression spring in said extension exerting a force on said abutment opposite to the force exerted thereon by said speeder spring.

25 5. Resetting means for a speed governor having a speeder spring and a manually movable abutment for said speeder spring comprising, a spring exerting a force directly on said abutment in a direction to load said speeder spring.

30 6. Resetting means for a speed governor having a compression speeder spring and a manually movable abutment for said speeder spring comprising, a compression spring exerting a force on said abutment in one position of said abutment 35 equal and opposite to that exerted by said speeder spring which force varies inversely as the force exerted by said speeder spring upon movement of the abutment in either direction from said one position.
